UNITED STATES PATENT OFFICE.

LAWRENCE E. SCRANNAGE, OF PHILADELPHIA, PENNSYLVANIA, ASSIGNOR OF ONE-HALF TO ALEXANDER CHAMBLEY, OF PHILADELPHIA, PENNSYLVANIA.

OIL RECTIFIER FOR INTERNAL-COMBUSTION ENGINES.

Application filed January 22, 1925. Serial No. 4,061.

This invention relates to oil rectifiers for internal combustion engines of the customary types and construction; and as is well known such engines are subject to oil pumping at the piston heads with attendant disadvantages, and the primary object of my invention is to effectively remedy the same.

Another object of this invention is the provision of a means effective to prevent the lubricating oil working upward past the piston-rings into the combustion space which forms carbon deposits upon the piston heads, combustion chamber walls, spark plugs, and valve heads thereby causing short circuits in the spark plugs and preignition.

A further object of this invention is a means effective to prevent excessive lubrication of internal combustion engine pistons; by automatically controlling such lubrication.

A still further object of this invention is to provide a novel form of piston for internal combustion engines and means controlling the lubrication thereof.

Another object of this invention is to provide a device adapted to refine the lubricating oil drawn from the reciprocating pistons and crank case individually or simultaneously. An important object of this invention is to provide a means for cooling the refined oil before mixing with the lubricating oil contained in the crank case.

Another object of this invention is to provide a valveless ported piston operative substantially throughout the entire stroke cycle whereby a much thinner lubricating oil may be used and thus reduce frictional losses to a minimum.

With the foregoing and other objects in view my invention comprehends its features of construction, combination, and arrangement of parts hereinafter fully described, illustrated by the accompanying drawings, and specifically pointed out in the appended claims.

In describing my invention in detail, reference will be had to the accompanying drawings wherein like characters denote the same or corresponding parts throughout the several views; and in which:

Figure 1, is a vertical section of an internal combustion engine cylinder including a typical embodiment of my invention.

Figure 2, is a front elevation of the novel type of piston associated in this invention; and,

Figure 3, is a sectional view taken as indicated by the arrows 3-3 in Figure 1, to better illustrate the thermostatic control.

Referring to the drawings, it will be observed that the internal combustion motor 10, is substantially of the usual form with the pistons and cylinder walls lubricated by any adequate splash or force-feed system. The motor cylinders may be air cooled or water jacketed as indicated at 11.

The reciprocating piston 12, at the head end, is provided with a plurality of piston rings 13 and 13'; of any desired type, while the piston wall is formed with a channel 14, extending around the entire peripheral surface between the two lower piston rings. I further provide a depending lug 15, Figures 1 and 2, below the skirt of the piston 12, with an external longitudinal channel or groove 16, in registration with a port 17, in the motor cylinder 10, extending a short distance above the bottom of the piston 12. The transverse channel 14 and longitudinal channel 16, are in communication by an internally ribbed passage 18.

Directly above the external longitudinal groove 16, is a second external longitudinal groove 19, separated therefrom by the piston wall 20; said groove 19 being also in registration with the port 17, during a portion of the stroke cycle as hereafter explained. The upper end of the groove 19 communicates with an external transverse channel 21, extending entirely around and beneath the lower piston ring 13'. Diametrically opposite the longitudinal grooves 16 and 19, I drill vent holes 22 and 24, inwardly, from the transverse circumferential external channels 14 and 21, through the piston walls 12; which holes are essential to effectually remove the surplus lubricating oil from the aforesaid channels as will be explained hereinafter.

It is desirable to subject the oil collecting channels 14 and 21, to a suction or exhausting action through a port 17, during the entire piston cycle for the effective removal of the liquid contents. Accordingly the port 17, when in register with the aforementioned longitudinal channels 16 and 19, subjects the upper and lower faces of the piston ring

13'—Figure 2—to an exhausting action during that portion of the stroke cycle which is most effective to collect the lubricant.

During the ascent of the piston 12, so long as any part of the channel 16 is in registration with the port 17, suction will be exerted upon the liquid collecting groove 14, and it is here to be noted that this suction or exhausting action takes place during the last half of the exhaust and compression stroke. The compression stroke is especially effective in forcing oil and unburnt gas downward past the piston rings which fact is utilized in the construction of the said piston 12.

During the descent of the piston 12, the lower faces of piston rings 13 and 13', are scraping excess oil from the cylinder walls. When that portion of the piston 20, between the upper and lower longitudinal grooves 16, 19, registers with port 17, the exhausting action is interrupted for a fraction of a second, only, when a longitudinal channel 19 registers with the port 17, thereby creating a suction or exhausting action upon the collecting channel 21. It is here to be observed that this exhausting action takes place during the last half of the piston suction stroke, when the tendency for oil to work upward past the piston rings to the combustion chamber is greatest.

The vents 22 and 22',—Figure 1—are effective in producing that difference in pressure requisite for efficiently and quickly removing the oil and other liquids collected in the channels 14 and 21—Figures 1 and 2—and they are shown diametrically opposite the port 17, although they may be placed elsewhere in the said grooves 14 and 21.

It is to be remarked that the means herein described produces a fluid collecting zone about the upper and lower faces of the lower piston ring 13', of the rapidly reciprocating piston 12, and such fluids and gases so collected are exhausted through the port 17, and distilled off as will be subsequently described. By this simple means surplus oil is prevented from working upward past the piston rings 13, 13' into the combustion space above the piston head and likewise any unburnt gases or liquids effective in producing crank case dilution, are simultaneously prevented from entering the crank case to pollute or thin the lubricating oil.

The suction port 17, connects into the valve spring chamber 23, common to a plurality of motor cylinders. The lower portion of the valve spring chamber 23, connects into the suction T 24, integral with the cooling reservoir casting 66, by pipe 25, and the upper portion of said valve spring chamber connects into said suction T by a pipe 26. One end of the suction T is in communication with the external retort chamber 27, by a pipe 28, while the other

end connects with the air valve 29, by a passage 30. An adjusting screw 31, is adapted to the suction T 24, to vary the port opening of the oil pipe 25 therein. A lock nut 32, secures the adjusting screw or needle valve 31, in any desired position.

A cover plate 33, and gasket 34, are bolted in gas tight relation to the top of the motor exhaust chamber 35; while concentrically secured to said cover plate I provide a deflector 36, and clamping nut 37, with a central passage 38, communicating into the intake manifold 39, by means of an elbow 40, conduit 41, and elbow 42.

A condenser 43, is positioned concentrically within the retort 27, the top of which is bolted gas tight to the conical depending funnel shaped cover 44, by bolts 45, the bottom flanges of which are secured with interposition of a gasket 46, to the bottom of the motor exhaust chamber 35, thus forming the bottom of the retort 27, condenser 43, as well as to support a thermostatically operated valve mechanism. Concentrically positioned and integrally cast to the condenser bottom 43, I provide a tubular member 47 snugly fitting the conical cover plate 44, at the upper end, and with a medial passage 48, enclosing a valve stem rigidly connected to a conical valve member 49, at the upper end, and to a conical valve member 50, at the lower end. Each valve is adapted to seat and effectually close the ends of the medial passage 48, as determined and fixed by the position of a thermostatic valve mechanism. An annular channel or groove 51, concentric with the smaller medial passage 48, and adapted to be closed by a valve 50 connects by a longitudinal passage 52, and a transverse passage 53 with the medial passage 48, and condenser interior 43, while the bottom of the condenser interior 43 connects through a passage 54, with the medial passage 48.

Referring now to the structural details of the thermostatic mechanism on the under side of—and supported by—the condenser bottom 43, as best shown in Figure 3, 55 represents a simple thermostatic element secured at one end by screws 56, or other hold-fast devices, to a depending lug of the condenser casting 43, effectual in transmitting heat to said element, and at the other end operative between spaced ears 57 of a T-shaped lever arm 58, fulcrumed at one end to the depending lug 59, of the condenser casting 43, by a pin rivet 60, the said ears being provided with adjusting screws 61 and lock nuts 62, to fix the range of deflection of the thermostatic element 55.

A valve arm 63, is provided with upturned ears 64 astraddle and pivoted to the depending lug 59 at the one end, and with a T-shaped formation at the other end adapted to carry tension springs 64', 64" in parallel

l spaced relation and connected at their pposite ends to the lateral projecting ears of the T lever 58. This valve lever 63 supports the air valve 29, and oil valve 50, which in the drawing are shown in closed position.

Just below the thermostatic element 55, I provide an air port 65, through the wall of the oil cooling reservoir 66, to the outside air, which operates to cool the thermostatic element 55, when the valve mechanism is in its lowest or open position, whence air is obviously drawn through the said port, striking upon and cooling said thermostatic element in passing upward past and through the valve 29, passage 30, and pipe 28, into the retort 27, by reason of the reduction in pressure therein.

It is desirable to cool the oil refined and purified before returning the same to the crank case as well as to settle out any impurities. To this end, I provide the cooling reservoir 66, with a concentrically spaced thin tube 67, within the oil reservoir and the open ends thereof are expanded outwardly to form an oil tight joint, and connected at the one end to the explosion mixture intake manifold 39, and at the other end with the extension of the carburetor passage 68, the inside of this tube forming the explosive mixture conduit and the outside the radiating surface. It is here to be observed, that the said tube 67 is a heat exchanger effectively transferring the latent heat of evaporation of the combustible mixture to the hot oil, and simultaneously transmitting the heat of the liquid or oil to the combustible mixture. This action results in the cooling of the oil on the one hand and the raising of the temperature of the combustible mixture on the other.

The oil contained in the oil reservoir 66, finds its way to the crank case through an overflow passage 69, and pipe 70, while a drain plug 71, is provided as a means for withdrawing impurities settling out of the oil.

The intake cover plate 72, is interchangeable with the carburetor flange 73, to permit use of the several types of commercial carburetors and vaporizers.

In the drawing the oil purifying device or rectifier is shown in the closed position as when the internal combustion motor is inoperative and cold. In operation the rapidly reciprocating piston 12, produces a series of intermittent suction strokes effectually reducing the pressure in the intake manifold 39, below that of the atmospheric; and in such rapid sequence as to cause the combustible mixture therein to flow at a high velocity at right angles to the passage 39' connecting with the elbow 42, conduit 41, elbow 40, and hollow clamping nut 37, into the retort 27, and effecting therein and in

the condenser 43, a sub-atmospheric pressure or vacuum. By means of the conduit 28, this sub-atmospheric pressure is tri-functionally effective at the suction T 24; firstly to exhaust air, gases, and liquids by way of the conduit 26, from the oil collecting channels 14, 21, longitudinal passages 16, 19, registering with the port 17, and port 17, into the valve spring chamber 23; secondly to exhaust the fluids in the chamber 23 into the suction T 24, by way of the conduit 25; and thirdly to effect a vacuum upon the passage 30, when the valve 29 is closed, as well as to exhaust air therefrom when said valve is open. The combination of this air, gas and liquid discharges into the retort 27, where distillation takes place. A portion of the heat of the motor exhaust gases traversing the exhaust chamber 35, are conductively absorbed by the fluids in the retort 27, raising the temperature of the liquid sufficiently to vaporize any acids, water, or fluid combustibles which are exhausted into the motor combustion chamber (not shown) by means of the passages connecting into the intake manifold 39, hereinbefore mentioned. These acids, water, and combustible vapors are exploded and expelled from the motor combustion space through the exhaust port 74 and hollow exhaust chamber 75 within the motor exhaust manifold 35. Meanwhile the fluids in the retort 27, have reached the point of ebullition, bubbling over into the condenser 43, through passages 48, 53 and 54, which process continues until such time as the heat of the liquid in retort 27, and condenser 43, attains parity and of a sufficient degree to downwardly deflect the thermostatic element 55, which depresses the T lever arm 58 below a plane passed horizontally through the pivot 60, thereof, whereby the parallel spaced springs 64, 64' move the valve arm 63 downwardly opening the air valve 29, and the oil release valve 50, and simultaneously closing the valve 49. The fluid contents of the condenser 43 now discharge into the oil cooling reservoir 66, and are replaced by an equal volume of air drawn in through the port 65, annular channel 51 and passages 52, 53, while air is simultaneously drawn through the port 65, and passage 30, past the needle valve 31, exhausting more fluid from the valve chamber 23, into the retort 27. It is here to be noted that oil or fluids are filling the retort 27, at any desired rate, as determined by the needle valve 31, while oil is emptying from the condenser 43, and that the sub-atmospheric pressure in the retort 27, valve spring chamber 23, and upon the valve members therein, as well as the reciprocating pistons 12, is uninterrupted. The air rushing in through the port 65, cools the thermostatic element 55, to a degree sufficient to contract the same upwardly, there-

by elevating the T-lever arm 58, past a horizontal plane through the fulcrum 60 thereof, whereby the aforementioned parallel spaced tension springs 64', 64' again actuate the valve arm 63, and effectually close the valves 29 and 50. This motion terminates the distillation cycle.

While distillation is taking place within the retort 27, and the condenser 43, the fluids heretofore discharged into the oil cooling reservoir are absorbing the latent heat of vaporization of the combustible mixture flowing at high velocity through the intake conduit 67, and manifold 39, to the motor, effectually cooling the oil and simultaneously raising the temperature of said combustible mixture. The volume of the said reservoir 66, is greater than that of the condenser 43, hence the condenser must discharge its contents several times before the oil reservoir will overflow through the passage 69, into the crank case of the motor 10. It is to be observed that heavy impurities settle out and may be drained off at 71, while the oil has been cooled sufficiently before discharging into the motor crank case 10. By virtue of the air port 65, above the liquid level of the oil cooling reservoir 66, no check valves are required in the oil discharge line to the crank case of the motor 10.

It is to be further remarked that the valve mechanism is controlled entirely by the thermostatic element 55, and that the needle valve 31, is manually adjusted to regulate the liquid level within the retort 27.

This new oil rectifier and purifying appliance may be adapted to any internal combustion engine; the conduit 26, being connected to the manifold common to a plurality of cylinders to effect suction, through an exhaust port of the same character as 17, upon the oil collecting channels 14, 21, as heretofore described, while the conduit 25, may be connected to the oil sump of the crank case of the motor 10. The device will then operate to simultaneously draw fluids from the oil collecting channels 14, 21, and from the oil sump of the motor crank case without affecting the distillation and cooling cycle heretofore explained.

Those skilled in the art will readily understand that this invention is not restricted to the exact form shown and described, but that it may be varied within comparatively wide limit without departure from the principle of the invention and without sacrificing any of its advantages.

Having thus described my invention what I claim is:

1. The combination with the cylinder of an internal combustion engine, of a lubricated reciprocating piston therein having an external transverse circumferential fluid collecting channel between the lower two piston rings, an external longitudinal channel

on the piston skirt and extension thereof, registering with a suction port in the cylinder side wall, an internal passage connecting the longitudinal channel and the transverse channel, a second external transverse circumferential fluid collecting channel below the lower piston ring, a piston ring in spaced relation to, and separating the upper and lower external transverse circumferential fluid collecting channels, a second longitudinal external channel in extended spaced non-communicating relation to the first longitudinal channel registering with the suction port in the cylinder side wall, the upper end connecting the second transverse external circumferential fluid channel, air inlet conduits diametrically opposite the longitudinal external channels extending inwardly from the transverse external circumferential fluid collecting channels to the closed head end of the hollow piston interior, the said suction port in the cylinder side wall adapted to register with the upper longitudinal external channel during the last half of the piston suction and power strokes, and with the lower longitudinal external channel during the first half of the piston compression and exhaust strokes, and means to exhaust the fluid contents through the suction port in the cylinder side wall registering with the channels connecting their companion transverse circumferential fluid collecting channels.

2. The combination with the cylinder of an internal combustion engine, of a lubricated reciprocating piston therein, a piston ring, transverse circumferential fluid collecting channels on the external face of the piston in parallel contact relation with the piston ring edges diametrically open to the hollow piston interior and to longitudinal external companion channels registering in spaced relation with a suction port in the cylinder side wall, means to admit air to the transverse channels and means to exhaust their fluid contents through said suction port in the cylinder side wall.

3. The combination with an internal combustion engine including a cylinder, of a lubricated reciprocating piston therein, a suction port through the cylinder side wall communicating with a valve spring chamber, conduits connecting into the top and bottom of the valve spring chamber and terminating in a suction T, a manually operated needle valve in said T, one end of the suction T passage opened and closed to the atmosphere by a thermostatically operated valve, the opposite end of said suction T communicating with an exhaust heated retort, a conduit communicating with the retort and the combustion engine fuel intake passage providing the means of exhausting oil, gases and vapors from the piston chambers and the valve spring chamber into the retort, a con-

denser within said retort, a thermostatically operated valve adapted to the condenser providing the means of filling and emptying the condenser, a reservoir below the said retort and condenser open to the atmosphere at the top and concentric with the motor fuel intake conduit, a fluid overflow conduit at the top of the reservoir communicating with the motor crank case, a drain plug at the bottom of the said reservoir and means to adapt a carburetor to the fuel intake conduit.

4. The combination with the cylinder of an internal combustion engine, of a reciprocatory ported piston having a plurality of transverse liquid collecting channels, conduits connecting said collecting channels with the hollow interior of said piston, longitudinally aligned spaced companion channels connecting the transverse liquid collecting channels at the one end and closed at the opposite ends, the longitudinal companion channels alternately registering with a suction port, through the cylinder side wall, and means to apply suction at said port to withdraw the fluid contents from the aforesaid channels.

5. In combination with the cylinder of an internal combustion engine, a reciprocatory piston, having a plurality of external circumferential fluid collecting channels individually communicating with the hollow piston interior and with external longitudinally spaced longitudinal grooves alternately registering with a suction port through the cylinder side wall, and means to apply suction at said port to withdraw the fluid contents from the aforesaid channels.

6. In combination, a valve spring chamber integral with the cylinder of an internal combustion engine, a reciprocatory piston, having a plurality of fluid collecting channels communicating individually with longitudinally non-communicating spaced grooves adapted to register alternately with a suction port through the cylinder side wall communicating with the valve spring chamber, means to admit air from the piston interior to the said fluid collecting channels, and means to apply suction to the valve spring chamber to withdraw the fluid, air and vapor contents of the aforesaid channels through the said suction port into the said valve spring chamber.

7. In combination, a valve spring chamber integral with the cylinder of an internal combustion engine, a reciprocatory ported piston having a plurality of external circumferential fluid collecting channels, means to admit air to said channels, means to withdraw air, gas, oil and vapors from the uppermost fluid collecting channel during the latter portion of the piston compression and exhaust strokes, means to withdraw excess lubricant from the lowermost fluid collect-

ing channel during the first portion of the piston suction and power strokes into said valve spring chamber, means to apply suction to said valve spring chamber to withdraw excess lubricant from the valve stems 70 into the aforesaid valve spring chamber and means to apply suction to withdraw air, oil, gases and vapors simultaneously from said valve spring chamber into a still, means to heat the said still externally with the exhaust gases from the internal combustion engine, means to automatically control the distillation of the contents of the said still, means to continuously withdraw volatiles from the still into the fuel intake conduit, 80 means to automatically discharge the refined contents of the aforesaid still without interrupting the vacuum pressure upon the aforesaid piston, the valve spring chamber 85 and the still, means to cool the refined and purified lubricant, and means to return the cooled lubricant to the engine.

8. In combination, a valve spring chamber integral with the cylinder of an internal combustion engine, a reciprocatory piston, 90 means to withdraw fluids from around said piston by suction into the said valve spring chamber, means to withdraw lubricant from the crank case, means to control the quantity of oil withdrawn from the crank case, and the aforesaid valve spring chamber, into a still, means to heat the contents of the said still by the exhaust gases of the engine, means to automatically control the degree of distillation, means to convey the volatile material of distillation into the engine intake manifold by the suction of the engine, means to collect the distilled lubricant, means to automatically discharge the distilled lubricant by gravity into a condenser, without interrupting the vacuum in said still, means to extract heat from the hot refined oil in said condenser by the combustible mixture flowing through the intake manifold to the engine, means to conduct the cooled lubricant to the engine and means to withdraw impurities from the aforesaid condenser.

9. In combination an oil rectifying apparatus comprising a cast metal still adapted to be heated externally by the exhaust gases of an internal combustion engine, a cast metal condenser internally concentric with said still and radially flanged at one end forming the bottom of the aforesaid still and the top of a unitary casting consisting of a suction T at its upper end, means to bolt an internal combustion engine carburetor to the lower end of a vertical metal intake tube connecting at right angles with the combustible fuel intake manifold of the engine, a reservoir external to, and concentric with the said intake tube, said reservoir open at the upper end to the atmosphere through a side wall port, a delivery pipe 115 120 125 130

near the top of said reservoir, means to connect the intake manifold passage with the top of the aforesaid still, means to connect said suction T with the top of said still, a needle valve in said T and a plurality of suction conduits terminating in the aforesaid T; the aforesaid cast metal condenser having a thermostat on its under side to

control simultaneously the movement of a positive air valve and a positive lubricant 10 discharge valve.

In testimony whereof, I affix my signature at Philadelphia, Pa., the 20th day of January 1925.

LAWRENCE E. SCRANNAGE.
